P.C.(57) **CLAIM**

The ornamental design for a duck float ring, as shown and described.

DESCRIPTION

FIG. 1 is a perspective view of the duck float ring in full lines.

FIG. 2 is a front elevational view of the duck float ring.

FIG. 3 is a rear elevational view thereof.

FIG. 4 is a left side view thereof.

FIG. 5 is a right side view thereof.

FIG. 6 is a top plan view thereof; and,

FIG. 7 is a bottom plan view thereof.

The broken lines showing in FIGS. 1, 2, 4, 5, 6 and 7 form no part of the claimed design.
